UNITED STATES PATENT OFFICE.

GEORGE ERNEST WHITEHOUSE, OF EDINBURGH, SCOTLAND.

CLAMPING MECHANISM OF LOOSE-LEAF LEDGERS AND KEY THEREFOR.

1,102,114.

Specification of Letters Patent. Patented June 30, 1914.

Application filed August 8, 1913. Serial No. 783,768.

To all whom it may concern:

Be it known that I, GEORGE ERNEST WHITEHOUSE, a subject of the King of Great Britain, residing at Edinburgh, Scotland, have invented new and useful improvements 5 in Clamping Mechanism of Loose-Leaf Ledgers and Keys Therefor, of which the following is a specification.

This invention relates to improvements in 10 loose leaf ledgers of the kind comprising clamping bars drawn together by tapes or cords wound on a rotary spindle carried by one of the clamping bars and rotatable by means of a removable key.

15 In loose leaf ledgers of this kind it has heretofore been known to provide a ratchet wheel and pawl to prevent backward rotation of the said rotary spindle, that is to say, rotation of this spindle in the direction 20 which allows unwinding or slackening of the said tapes or cords, and to provide means for withdrawing the pawl from the ratchet wheel when desired.

25 The present invention provides improved means for withdrawing the pawl and retaining it thus withdrawn.

According to the present invention, the 30 pawl is provided with an arm lying adjacent to one end of the spindle so that it can be moved by a convenient part of a key to withdraw the pawl from the ratchet when the said key is slid to one position along the spindle and turned. Means are provided for retaining the said key in the position in 35 which it holds the pawl away from the ratchet wheel. In another position of the said key, while it is still in engagement with and capable of communicating rotary motion to the spindle, the pawl is left free to engage 40 the ratchet wheel and prevent unwinding of the cord wound on the spindle.

In the accompanying drawings:—Figure 1 is a view partly in central section showing a pair of clamping bars having the present 45 improvements applied thereto. Figs. 2 to 7 are detail views drawn to a larger scale. Fig. 2 is a plan of part of a bar showing the improved ratchet mechanism mounted thereon. Fig. 3 is an end view of the said bar. Fig. 4 shows a section of the line $x-x$, Fig. 2. Fig. 5 is a side view, and Fig. 6 an end view of a key for operating the said ratchet mechanism. Fig. 7 shows a section on the line $y-y$, Fig. 5.

55 Referring to the drawing, a is a spindle mounted to rotate in bearings b provided on

a bar c , to wind up or slacken tapes d , the ends of which are attached to a bar e . A ratchet wheel f , is mounted on the spindle a and is restrained from backward rotation by 60 a pawl in order to prevent unwinding of the tapes, in the well known manner. This pawl g controlled by a spring h , is formed with an arm i . The end of the spindle a is flattened to be engaged by a key j the barrel of which 65 is cut away to form a finger k . The interior of the key barrel is formed with flat surfaces l to fit the end of the spindle a , and a spring m is provided within the said barrel. The interior of the key barrel next to the 70 flat surfaces l is cylindrical as at m' , and is of sufficient diameter to allow the flattened end a' of the spindle to turn freely therein, while the part a^2 of the spindle next to the flattened end a' is of reduced diameter for a 75 similar reason. The key is also formed with an exterior lug or projection n .

An end plate o of the bar c has a hole p therein through which the key j can be introduced to engage the spindle a . This hole 80 is formed with enlargements q , r through which the lug n can pass. On the inner side of the plate o a catch plate s is provided having a hole therein corresponding to the shape of the hole p with its enlargements q 85 and r . A notch t is also formed in the said catch plate s but there is no corresponding notch in the plate o .

Assuming that the tapes d are wound up, and that it is desired to slacken them, the 90 key j is slid on to the spindle a in such a position that the lug n passes through the enlarged part q of the hole p , and by this movement of the key the spring m is compressed. The finger k is thus brought beneath the arm i and the lug n is brought to the inner side of the catch plate s . The flattened end a' of the spindle is then within the cylindrical part m' of the key. The key is then turned in a clockwise direction (refer- 100 ring to Fig. 3). During this movement, by reason of the action of the spring m the lug n slides in contact with the catch plate s and in due course enters the notch t so that the key is locked against further movement until 105 force is applied to compress the spring m and move the key so that the lug n is carried out of the said notch.

As the key is rotated so as to bring the lug n into position opposite the notch t , the finger k thrusts back the arm i and thus withdraws the pawl g leaving the ratchet

wheel *f* and the spindle *a* free to rotate in either direction.

To effect the rewinding of the tapes, the key is thrust in against the resistance of the spring *m* so that the lug *n* is carried out of the notch *t*. The key is then turned in the clockwise direction (Fig. 3) and the spring *m* is allowed to move the key so that the lug *n* passes through the enlarged part *r* 10 of the hole *p*. The flat surfaces *l* are then in engagement with the correspondingly flattened end *a'* of the spindle. When the lug *n* moves to the outside of the plate *o*, the finger *k* is moved to the right of the arm *i*. The spring *m* is arranged to thrust the key, when the latter is free, to this position so that it can be then rotated to wind up the tapes *d* without engaging the arm *i*.

In a preferred construction, as shown in 20 the drawings, ports *3*, *3* are provided, screwed into one bar and passing freely through holes in the other bar to keep the bars in alinement or parallelism, and these posts may comprise sections *3^a*, *3^b*, *3^c*, etc., 25 screwed together to vary the length of the posts.

I claim:

1. In a loose leaf ledger, a tape-winding spindle, a ratchet wheel on the said spindle, 30 a pawl adapted to engage the said ratchet wheel, a key for retracting the said pawl from the said wheel, and a catch plate for retaining the said key in operative relation to the said pawl.

35 2. In a loose leaf ledger, a tape-winding spindle, a ratchet wheel on the said spindle, a pawl adapted to engage the said ratchet wheel, an arm connected with the said pawl, a key adapted to move the said arm to retract the said pawl from the said wheel, and 40 a catch plate for retaining the said key in engagement with the said arm.

3. In a loose leaf ledger, a tape-winding spindle, a ratchet wheel on the said spindle, 45 a pawl adapted to engage the said ratchet wheel, an arm connected with the said pawl, a key adapted to move the said arm to retract the said pawl from the said wheel, a lug on the said key, and a catch plate having 50 a notch therein to receive the said lug.

4. In a loose leaf ledger, a tape-winding spindle, a ratchet wheel on the said spindle, a pawl adapted to engage the said ratchet wheel, an arm connected with the said pawl, 55 a key adapted to move the said arm to retract said pawl from the said wheel, a lug on the key, a catch plate, and a spring for thrusting the said lug against the said catch plate.

60 5. In a loose leaf ledger, a tape-winding spindle, a ratchet wheel on the said spindle, a pawl adapted to engage the said ratchet

wheel, a key for retracting the said pawl from the said wheel, a catch plate having a hole therein through which the said key can pass, 65 a lug on the said key, a spring arranged to thrust the said lug against the said catch plate, and an end plate having a hole therein through which the said key can pass, in alinement with the hole in the catch plate. 70

6. In a loose leaf ledger, a tape-winding spindle, a key adapted to be slid on to the end of the said spindle, a spring within the key barrel, and a catch plate for retaining the said key on the spindle against the 75 thrust of the spring.

7. In a loose leaf ledger, a tape-winding spindle, a key adapted to be slid on to the end of the said spindle, a lug on the exterior of the key barrel, and a catch plate having a notch therein to receive the said lug and thereby obstruct removal of the key from the spindle.

8. In a loose leaf ledger, a tape-winding spindle, a key adapted to be slid on to the 85 end of said spindle, a spring within the key barrel, a lug on the exterior of the key barrel, and a catch plate having a notch therein into which the said lug is adapted to be pressed by the said spring.

9. In a loose leaf ledger, a tape-winding spindle, a key adapted to be slid on to the end of the said spindle, a lug on the exterior of the said key, and a catch plate restricting withdrawal of the key from the 95 said spindle.

10. In a loose leaf ledger, a tape-winding spindle, a ratchet wheel on the said spindle, a pawl adapted to engage the said ratchet wheel, a key adapted to be slid on to the end 100 of the said spindle, a finger formed thereon, and an arm adapted to be engaged by the said finger to move the said pawl.

11. In a loose leaf ledger, a tape-winding spindle having flats at one end thereof and 105 a reduced cylindrical part adjacent to the said flats, a key having a tubular barrel with flats within its outer end and an enlarged cylindrical chamber therein adjacent to the said flats, a spring within the key barrel 110 adapted to thrust against the spindle end, and means for preventing the key from being moved by the said spring.

12. A loose leaf ledger key comprising, in combination a barrel portion, a lug on 115 the exterior of the barrel, flats within one end of the barrel, an enlarged cylindrical chamber adjacent to the said flats, and a spring within the said barrel.

GEORGE ERNEST WHITEHOUSE.
